FOREIGN PATENT DOCUMENTS

WO WO 00/51076 8/2000

Primary Examiner—Sandra Morris

(74) *Attorney, Agent, or Firm*—Mark A. Litman & Associates, P.A.

(57) **CLAIM**

The ornamental design of a card dealing dispenser, as shown and described.

DESCRIPTION

FIG. 1 is a perspective view of a card dealing dispenser from a rear to forward angle showing our new design.

FIG. 2 is a perspective view of a card dealing dispenser from a rear to forward angle showing our new design, with functional elements shadowed in FIG. 1 removed.

FIG. 3 is a left side view of a card dealing dispenser.

FIG. 4 is a top view of a card dealing dispenser.

FIG. 5 is a bottom view of a card dealing dispenser.

FIG. 6 is a right side view of a card dealing dispenser.

FIG. 7 is a rear view of a card dealing dispenser; and,

FIG. 8 is a front view of a card dealing dispenser.
